UNITED STATES PATENT OFFICE.

VICTOR H. JENNINGS, OF WORCESTER, MASSACHUSETTS, ASSIGNOR, BY MESNE ASSIGNMENTS, TO UNIVERSAL PATENTS COMPANY, OF WOONSOCKET, RHODE ISLAND, A CORPORATION OF RHODE ISLAND.

WOVEN CARRIER.

1,252,268.

Specification of Letters Patent.

Patented Jan. 1, 1918.

Application filed June 24, 1916. Serial No. 105,673.

To all whom it may concern:

Be it known that I, VICTOR H. JENNINGS, a citizen of the United States, residing at Worcester, in the county of Worcester, State 5 of Massachusetts, have invented a certain new and useful Improvement in Woven Carriers, of which the following is a specification, reference being had thereto to the accompanying drawings.

10 Figure 1 of the drawings is a front elevation of a woven carrier embodying the invention, with the pockets thereof occupied by various articles.

Fig. 2 is a view in section in the plane indicated by line 2—2, Fig. 1, with the articles removed from the pockets.

The carrier shown in the drawings is a so-called engineers' pencil case, designed for convenient attachment to a garment worn 20 by the user, and contrived to hold or carry conveniently for handy use certain of the articles which frequently are used by him. The articles provided for in this instance are five pencils *a*, *a*, etc., of different kinds, 25 a pencil eraser, and a so-called alidade *b*. For the reception of the pencils it is furnished with pencil-loops *c*, *c*, etc. For the reception of the pencil eraser, it is furnished with a short pocket *d*, shaped and proportioned to receive an oblong block or strip 30 of eraser material. A cover-flap *e* is furnished in connection with eraser pocket *d*. Said cover-flap is fixed by one end to the backing of the carrier. It is shown furnished with a suitable stud-and-socket fastening *e'* for keeping it closed in place. For 35 the reception of the alidade, the carrier is furnished with a long pocket *f* somewhat larger in its capacity than one of the pencil-loops.

40 The eraser pocket and alidade pocket are proportioned and formed to fit the eraser and alidade snugly and hold them securely.

To a certain extent the carrier shown in the drawings is simply an illustrative embodiment of the invention. The number of 45 pockets and their arrangement may vary, and they may be contrived to receive additional or different articles.

A carrier embodying the invention comprises, essentially, flexible backing having 50 formed thereon loops and pockets on the order of those just mentioned, and having also sheaths which are occupied by stiffening material in strip form.

The backing is composed of a back ply *g*, 55 an intermediate ply *h*, and portions of a ply *i* of which the loops and pockets are formed. It is continued in the form of a wall *k* composed of back ply *g* and intermediate ply *h* a short distance above the upper 60 ends or mouths of the loops and pockets. At *m* and *n* are web-extensions or flanges at top and bottom of the backing furnished with eyelets *o*, *o*, through the holes of which may be passed the pointed portions of safety 65 pins *p*, *p*, used in attaching the carrier to a garment of the user. The said extensions or flanges are sufficiently thin and flexible to enable them to be bent or doubled more or less to facilitate the application of the 70 pins to the eyelets, and the engagement of the pins with the coat or shirt of the user of the carrier. Preferably they are constituted of portions of the back ply *g*, alone. One or more supplemental eyelets *r*, applied 75 to the upper one of the said extensions may be occupied by a cord or cords for connecting the eraser and alidade, or other articles, flexibly with the carrier, as in the case of the cord *s* shown connected to the said extension and to the alidade.

The sheaths *t*, *t*, etc., containing the strips *u*, *u*, etc., of flexible stiffening material extend lengthwise of the loops and pockets, and parallel with the latter. They are 85 formed between the back ply *g* and the intermediate ply *h*, by connecting the said two plies together between sheaths and leaving them disunited for the production of the sheaths. The strips *u*, *u*, etc., which 90 are slipped lengthwise into the sheaths may be composed of various materials, but usually I employ that known in the market as walohn, which has a very satisfactory degree of comparative stiffness combined with 95 flexibility, resiliency, and toughness. The sheaths extend above the upper ends of the loops and pockets, namely within the wall *k*, and the upper portions of the flexible stiffening strips also extend above said upper 100 ends.

The loops and pockets are at the exterior of the intermediate ply *h*. The eraser pocket *d* and alidade pocket *f* are formed with closed bottoms. The pencil loops are open 105 at both ends. Their lower portions are occupied by long sleeve-like metal cups *v*, one of which is partly shown where the material

inclosing the same is broken away in part. These cups are clasped tightly by the surrounding portions of the loops, so that they are prevented by frictional engagement with 5 their exterior surfaces from becoming displaced lengthwise within the loops. They receive the inserted pointed ends of the pencils, and protect the points of the latter. They are so proportioned that the pencil 10 ends fit snugly within the same and are effectively retained by the frictional engagement of the sleeve-portions of the cups with such ends.

The carrier with its pockets filled with 15 tubes, pencils, eraser, and alidade may be rolled upon itself transversely into approximately a cylinder of comparatively small diameter and carried in one of the user's pockets. The stiffening keeps the carrier 20 straight lengthwise so that the loops and pockets and the wall $\frac{1}{8}$ above the same are held from buckling or bending. Consequently, no difficulty is experienced in inserting the pencils, eraser, and alidade into 25 their respective loops or pockets. The stiffening means constitutes a reinforcement which reduces the liability of bending of the wearer's body to cause breakage of pencils.

30 The carrier may be made of separate webs of material, by securing the back and intermediate ones together between the sheaths, and forming a third web into the loops and pockets and securing the same to the face 35 of the intermediate web between the loops and pockets. Preferably, the carrier is produced substantially complete in a loom, omitting the stiffening material and the metal cups, by producing the back ply, the intermediate ply, and the loops and pockets in the weaving as integral portions of one combination web, all by processes which will be understood by those skilled in the art of weaving. In such case the sheaths for the 40 reception of the stiffening material are formed between the back ply and intermediate ply by leaving such two plies disunited as and where required for the production of such sheaths. After the insertion 45 of the strips of stiffening material into the sheaths, the upper ends of the latter are closed, in either method of manufacture, by one or more lines w, w , of stitches above the upper ends of the said strips. The loops 50 and pockets are formed in the production of the loop ply and in the weaving the latter is joined to the other two plies. The bottom ends of the eraser pocket and alidade pocket are woven closed in one of the known 55 ways, or as may be preferred. Preferably the bottom ends of the pencil loops are woven open, but contracted or constricted as indicated in Fig. 1 of the drawings so as to keep the cups from working down 60 through openings. The contraction or con-

striction is produced by subjecting the warp-threads of the said bottom ends to a heavier degree of tension than those employed in weaving the other portions of the loops.

When the unfinished carrier is produced 70 by weaving the same substantially as a complete article, the top and bottom edges of the backing are selvage edges and the sheaths, loops and pockets are produced transversely of the carrier-web. A connected sequence of carrier-sections is produced by continuation of the weaving operations, they being separated after the conclusion of the said operations by cutting transversely across the portions of web which connect 80 them together in a longitudinal series. Usually, the warp-threads of the intermediate and loop-and-pocket plies are simply floated between one series of loops and pockets and the next, without interweaving with 85 weft or filling, and after the carrier-sections have been separated from one another by cutting across the back ply on intermediate transverse lines the loose ends of warp-threads projecting at the sides of the first 90 and last pencil loops are trimmed away. The cut edges of the back ply are folded over upon themselves and upon the cut edges of the intermediate ply and loop-and-pocket 95 ply, as shown at x, x , Fig. 2, and the folded-over portions are secured in position by means of lines of stitches y, y . The corners z, z , of the top and bottom extensions of the backing are turned over and stitched down, as a good finish.

100 What is claimed as the invention is:—

1. A carrier of woven material comprising a flexible backing, elongated pockets or loops of such material at the surface of said backing, and a plurality of stiffening strips 105 combined with said backing and paralleling said pockets or loops.

2. A carrier adapted to be doubled or rolled upon itself transversely, comprising a flexible backing having a plurality of 110 elongated pockets or loops upon its face, and also having a plurality of sheaths paralleling the said pockets, and strips of flexible stiffening material occupying 115 said sheaths.

3. A carrier adapted to be doubled or rolled upon itself transversely, comprising a flexible backing having a plurality of elongated pockets or loops upon its face and also having a plurality of sheaths paralleling the said pockets, and a plurality of 120 strips of flexible stiffening material occupying said sheaths and extending a distance above the upper ends of the pockets or loops.

4. A carrier comprising a flexible backing composed of a back ply and a second ply secured to said back ply with intermediate 125 sheaths, a plurality of elongated pockets or loops upon said second ply, and a plurality 130

of flexible stiffening strips occupying said sheaths and paralleling said pockets or loops.

5. A carrier of woven material comprising a flexible backing, elongated pockets or loops at a surface of said backing, a plurality of stiffening strips combined with said backing and paralleling said pockets or loops, and a flexible extension or flange 10 above the upper ends of said stiffening strips having eyelets for an attaching pin or pins.

6. A carrier of woven material comprising a flexible backing, elongated pockets or loops at a surface of said backing, a plurality of stiffening strips combined with said backing and paralleling said pockets or loops, and flexible extensions or flanges 20 respectively above the upper ends of said stiffening strips and below the lower ends thereof having eyelets for attaching pins.

7. A carrier of woven material comprising a flexible backing, elongated pockets or loops at a surface of said backing, said 25 backing extending above the upper ends of said pockets or loops, a plurality of stiffening strips combined with said backing, paralleling said pockets or loops, and extending above the said upper ends thereof, and 30 a flexible extension or flange above the said stiffening strips having provisions for attachment to a garment of the wearer.

8. A woven carrier comprising a flexible 35 backing composed of a back ply, a second ply secured to said back ply with intermediate sheaths, a plurality of elongated pockets or loops upon said second ply, all integral with one another as woven, and a plurality of flexible stiffening strips occupying said 40 sheaths and paralleling said pockets or loops.

9. A woven carrier comprising a flexible 45 backing composed of a back ply, a second

ply secured to said back ply with intermediate sheaths, a plurality of elongated pockets 45 or loops upon said second ply, all integral with one another as woven, and a plurality of flexible stiffening strips occupying said sheaths and paralleling said pockets or loops, and extending within said sheaths a 50 distance above the upper ends of the pockets or loops.

10. A carrier comprising a flexible backing woven with a plurality of elongated pockets or loops upon its face, and with a 55 plurality of sheaths paralleling said pockets or loops, and a plurality of strips of stiffening material occupying said sheaths.

11. A carrier comprising a backing woven with elongated pockets or loops, and sleeve-like cups occupying the lower ends of said 60 pockets or loops.

12. A carrier comprising a backing woven with elongated pockets or loops, and having contracted or constricted open lower ends, 65 and sleeve-like cups occupying the lower ends of said pockets or loops.

13. A carrier comprising a backing woven with elongated pockets or loops, and with an extension having provision for attachment to a garment of the user, and sleeve-like cups occupying the lower ends of said 70 pockets or loops.

14. A carrier comprising a backing woven with elongated pockets or loops, and having contracted or constricted lower ends, and with an extension having provision for attachment to a garment of the user, and sleeve-like cups occupying the lower ends of said 75 pockets or loops.

In testimony whereof I affix my signature in presence of two witnesses.

VICTOR H. JENNINGS.
